VENDING MACHINE

Philip C. Hughes, Brooklyn, N. Y.,

Application June 10, 1936, Serial No. 84,403

4 Claims. (Cl. 221—123)

This invention relates to vending machines, and has for an object to provide an improved construction for stirring the articles to be vended shortly before they are vended or discharged from the machine.

Another object of the invention is to provide a vending machine wherein the coin used in releasing an article also acts as a connector for causing the actuating mechanism of the machine to operate the stirring device each time an article is vended.

An additional object of the machine is to provide a construction whereby the actuating lever forming part of the machine must be completely actuated after the insertion of a coin before a second coin can be utilized.

In the accompanying drawings:

Fig. 1 is a view partly in elevation and partly in longitudinal section disclosing an embodiment 20 of the invention, the sectional part being taken on the line 1—1 of Fig. 2;

Fig. 2 is a vertical sectional view through Fig. 1 at approximately right angles to the showing of Fig. 1;

Fig. 3 is a horizontal sectional view through Fig. 1 approximately on the line 3—3;

Fig. 4 is a fragmentary sectional view through Fig. 1 approximately on the line 4—4;

Fig. 5 is a horizontal sectional view through Fig. 1 approximately on the line 5—5;

Fig. 6 is a fragmentary enlarged sectional view through Fig. 1 approximately on the line 6—6;

Fig. 7 is a view similar to Fig. 6 but on a reduced scale and showing only the actuating lever, 35 quadrant and immediate associated parts;

Fig. 8 is a plan view of a gear and pinion disclosing certain features of the invention;

Fig. 9 is a detail fragmentary sectional view illustrating the lower part of the coin chute and 40 associated parts.

Referring to the accompanying drawings by numerals, 1 indicates a casing which may be cast metal or any other desired material, said casing being provided with a base 2 and a flaring cup-shaped top 3 having an annular flange 4. As illustrated in Fig. 1 the casing 1 is hollow and formed with annular offsets 5 and 6 for receiving respectively the supporting frame 7 and the cover plate 8. Above the casing 1 is positioned a top 9 which may be of any desired material, preferably of transparent glass and also preferably formed with an annular flange 10 adapted to rest on flange 4. The flanges 4 and 10 are adapted to be connected by suitable means, as for instance an annular strap 11 U-shaped in cross section held together by the bolt of a padlock 12 or other suitable means. If desired, a gasket 13 could be positioned between the flanges 4 and 10. By forming the top 9 of clear or transparent glass the contents of the bowl 14 may be readily seen and also

the action of the stirring arms 15 may be observed. The bowl 14 may be of glass though preferably it is of sheet metal and provided with a stiffening roll 16 at the upper edge, while at the center of the bottom is provided with an aperture 17, and adjacent this aperture, namely at point 18, is welded, soldered or otherwise rigidly secured to the upper part of the gear ring 19. The gear ring 19 is provided with internal gear teeth continually meshing with the gear wheel 20 which 10 functions as hereinafter described to rotate the gear ring 19 and bowl 14.

From Fig. 1 it will be observed that a peripheral groove is formed in ring 19 for receiving ball-bearings 21 which are held in place by a suitable cone 22 whereby the parts are easily rotated and friction is reduced to a minimum. In regard to the plate 8 the same is preferably held in position by friction though it could be secured in place by a screw or other fastening means. The same is true 20 in respect to the frame 7, which frame is preferably a casting. The supporting frame 7 is provided with suitable bores, bosses and other parts as hereinafter fully described for supporting properly certain parts.

As shown in Fig. 1 there is provided a bore 23 into which the reduced end 24 of shaft 25 extends. A suitable rivet 26 rigidly connects shaft 25 to the frame 7 so that this shaft is held stationary. Mounted on shaft 25 is a hollow double cone deflector or guard 27 which is rigidly clamped in place by reason of the threaded part 28 of the shaft being screwed tightly into a threaded socket in the auxiliary shaft 25'. The various arms 15 are rigidly secured in any desired manner to the 35 enlargement 29 of the shaft 25' whereby these arms are held stationary while the bowl 14 rotates. The material being vended is placed in the bowl 14 and by reason of the fact that this material is supported by the bowl, a rotary movement 40 is given to the material and the stationary functioning of the arms 15 will thereby result in mixing and agitating the material. It will be understood that any desired articles may be vended. As illustrated particularly in Fig. 4, almost 45 rectangular articles are shown as being vended by the machine. These articles may be solid pieces of material or may be capsules with other articles mounted therein. The material or the particular articles to be vended form no part of the present 50 invention, except that they should be of substantially the shape shown in Fig. 4 so that they may be properly fed into the vending chute hereinafter fully described.

The bottom of the double cone 27 is provided 55 with a spiral wall 30 which does not quite contact with the upper surface of the bottom of bowl 14 so that articles 31 from the bowl 14 may be readily moved by the friction of the bowl into the spiral runway 32 and be guided thereby 60

into the discharge chute 33 which is stationary and which is preferably connected with wall 30 and with the frame 7. After the articles 31 have entered the chute 33 for an appreciable distance 5 they will move down under the action of gravity and also under the action of the articles in the rear thereof so that eventually they will drop into the pocket member 34 which is slidably mounted on frame 7. This pocket is shown particularly in Figs. 1 and 6.

L-shaped slideways 35 are connected by welding or otherwise to the frame 7, and the metal of which pocket member 34 is formed is provided with a platform 36 resting on the slideways 35. 15 One part of the platform, namely part 36', is offset downwardly as shown in Fig. 1 and has an actuating tongue or member 37 connected therewith, said tongue or member 37 being in the path of movement of the pin 38 whereby 20 when this pin is moved over to the position shown in Fig. 6, pocket member 34 will be moved to the left against the action of spring 34' as shown in Fig. 1 until the article 31 is opposite the entrance 39 of the vending chute 40. This chute is 25 shown in side elevation in Fig. 2 and is provided with a depressed portion 41 whereby the article 31 will stop in the depression 41 and the person operating the device may pass his hand through the opening 42 and pick up the article when desired. 30 When the article 31 reaches the depression 41, the article has been dispensed as far as the machine is concerned.

In order to secure the action above described certain mechanism is used as shown more particularly in Figs. 1, 6, and 7. From these figures it will be observed that there has been provided a rock shaft 43 having the upper end suitably mounted in a ballbearing journal structure 44 carried by the frame 7. The lower end is rotatably fitted in the base plate 45 as shown in Fig. 2. A member 46 is rigidly secured to the shaft 43, said member having an arc-shaped outer surface and a projection 47 to which one end of the retractile or spring 48 is secured. The 40 opposite end of spring 48 is connected at 49 to a suitable fitting secured to the base 2. This spring is normally under some tension but when moved to the position shown in Fig. 7 it is under some appreciable tension and continually tends to move the member 46 towards the left as illustrated in Fig. 7. It is to be noted that the spring 48 rocks the shaft 43 to the left and that the actuating lever 50 rocks the shaft 43 to the right 50 as shown in Fig. 7.

In order to secure this result it is to be noted that the lever 50 is integral with the quadrant 51 though it could be made separate and rigidly secured thereto. Quadrant 51 is a little more 60 than a half circle and is rotatably mounted on shaft 43, the mounting being a suitable ballbearing structure 52 carried by the shoulder 53 formed on shaft 43. The quadrant 51 is preferably provided with reinforcing flanges 54 and 55 so as to stiffen the periphery of the quadrant. Flange 55 is provided with an inwardly extending lug 56 shown particularly in Fig. 7. Associated 65 with the quadrant 51 is a ratchet 57 having suitable ratchet teeth 58 adapted to coact with the spring-pressed pawl 59. From Fig. 7 it will be observed that one tooth, namely tooth 60, is taller than the remaining teeth so that when the pawl 59 is disengaged the ratchet 57 may quickly move past the pawl without danger of striking any 70 of the teeth 58. A rack 61 is rigidly secured to

the ratchet 57 in any desired manner, as for instance by welding or by being held thereby by suitable screws 62. This rack carries the pin 38 and also the pin 63. The gear teeth 64 on rack 61 extend approximately a quarter of a circle and continually mesh with the pinion 65 as shown in Fig. 6.

Pinion 65 is keyed or otherwise rigidly secured to shaft 66 which is rotatably mounted in frame 7 and which at the upper end is rigidly secured to a ratchet wheel 67 shown in detail in Fig. 8. A gear wheel 68 is rotatably mounted on the upper end of shaft 66 and carries a spring-pressed pawl 69 which continually engages the ratchet wheel 67. By reason of this construction when shaft 66 rotates in one direction gear wheel 68 will rotate, but when shaft 66 rotates in the opposite direction gear wheel 68 will remain stationary. A pinion 70 continually meshes with gear wheel 68, said pinion being preferably rigidly secured to a shaft 71 carried by suitable ballbearing journal members fitted into the frame 7 as shown in Fig. 1. The upper end of shaft 71 has the gear wheel or pinion 20 rigidly secured thereto whereby the bowl 14 may be rotated but only in one direction, and the direction of this rotation is indicated by the arrow 72 shown in Fig. 4.

The frame 7 is formed with a depending member or boss 73 (Fig. 6) which carries the journal pins 74 and 75 as shown in Figs. 6 and 7. Journal pin 75 is the pin on which the pawl 59 is pivotally mounted. This pawl is provided with a release extension 76 and is also provided with a spring 77 which acts against the hook-shaped leg 78 of the bell crank lever 79 rotatably mounted on pin 74 whereby the pawl 59 is pressed against the ratchet 57 unless held out of contact by the lug 56 pressing against extension 76 as shown clearly in Fig. 6. The leg or end 80 of bell crank lever 79, 40 coacts with the pin 63 for swinging the bell crank lever out of the path of movement of lug 56 as shown in Fig. 4 until lug 56 has caused a disengagement of pawl 59.

The device is a coin controlled device wherein 45 the inserted coin is in the mechanical circuit or forms a mechanical connector between the power member, namely lever 50, and the actuated parts. As shown in Fig. 2, the coin is inserted into the coin chute 81 at opening 82 and if it is of the proper size it will slide down the coin chute to the lower end thereof as illustrated in Fig. 9. Adjacent the lower end of chute 81 there is provided a hinged member 83 pivotally mounted at 84 on the chute and provided with a pair of lugs 85 which are adapted to swing beneath the chute 81 so as to catch the coin. The member 83 is actuated by gravity and normally remains so that the lugs 85 will be beneath the coin chute. However, when lever 50 is moved over to the position 60 shown in Fig. 6, quadrant 51 will move in alignment with the lower end of coin chute 81. Before this has taken place the extension 86 of the ratchet 57 moves beneath the chute and swings the plate or member 83 out of the way, whereupon 65 the coin drops into the opening or slot 87 of extension 86. As soon as quadrant 51 is brought into register with slot 87 the coin will drop downwardly and extend through the slot 88 of quadrant 51 and will rest on the surface 89 (Fig. 2) 70 forming part of the coin discharge chute 90. The coin discharge chute 90 extends to the coin box 91.

After the coin has arrived at the position shown in Fig. 9, which is the same position as shown in Fig. 6, lever 50 is grasped and swung until it 75

strikes the edge 82 as shown in Fig. 7. As the coin connects quadrant 51 and extension 86 of ratchet 57 the swinging movement of the quadrant will also swing the ratchet 57 and the rack 61 around 5 to the position shown in Fig. 7 against the action of spring 48, whereupon pawl 59 snaps in back of the special high tooth 60. As soon as the lever 50 has reached the point just described it is released or given a slight shaking movement, where- 10 upon the coin will drop down into the chute 90 as it is immediately above the open part of this chute when the parts are in the position shown in Fig. 7. The swinging of the parts to this position will partly rotate shaft 43 and will bring 15 the spring 48 under tension.

Lever 50 and quadrant 51 are both loose after the coin has been dropped, but in order to eject or discharge the article 31 from pocket member 34 it will be necessary to move the lever 50 back 20 to the position shown in Fig. 6. As the lever and quadrant are moved back lug 56 will strike the hook-shaped lug 78 and thereby snap past this member. If it is moved no further it is locked against a return movement. However, the proper 25 practice is to move lever 50 and lug 56 as far as possible toward the edge 83. When this is done lug 56 strikes the extension 76 and swings pawl 59 away from the high tooth 60. As soon as this has been accomplished spring 48 will immediately 30 function and quickly swing the ratchet 57 and the rack 61 to the position shown in Fig. 6, whereupon pin 38 will press the tongue or extension 37 and move the socket 34 to the dotted position shown in Fig. 1, whereupon the article 31 carried 35 in this pocket will be allowed to drop by gravity into the vending chute 40. After this has been done lever 50 and quadrant 51 may be swung back and forth without securing any results whatever. Also when this has been accomplished the exten- 40 sion 56 will have moved automatically to a position beneath the chute 81 so as to receive a coin therefrom whenever a coin has been inserted into opening 82.

A suitable stop 94 has been provided for stopping the swinging movement of shaft 43, rack 61 and the extension 86 so that the opening 87 thereof will automatically be brought into alignment with the chute 81. When a second coin is inserted it will automatically move downwardly 45 and project through slot 87 and rest on the upper surface of quadrant 51. It is then only necessary to swing the lever 50 and quadrant 51 around until lever 50 strikes point 82 in order to align slot 88 of the quadrant with the slot 87 of 50 the extension 86. By reason of the construction just described it will be seen that when the lever 50 is moved around to the position shown in Fig. 7 the bowl 14 will remain stationary, but when spring 48 is allowed to function it will rotate the 55 bowl 14 and thereby cause a stirring action in order to stir the various articles 31 so that they will not adhere and so that they may be properly fed into the guideway 32. No particular or definite article can be directed into this guideway but 60 eventually all of the articles in the bowl will be fed into this guideway and finally discharged as 65 above set forth.

As illustrated particularly in Fig. 2, the coin chute 82 is adapted to receive a coin of a certain size, as for instance a five cent piece. Where coins of smaller sizes are inserted, as for instance a one cent piece or a ten cent piece, said smaller coins will pass through the opening 85 in the

bottom of the chute 81 and be discharged into the auxiliary chute 96 which extends downwardly and is connected at 97 to the vending chute 40. By reason of this construction only coins of the proper size may be used as larger coins could not 5 be placed into chute 81, and the smaller coins will be directed into the vending chute 50 so that a person may readily recover the coins by placing the hand into the depressed portion 41.

I claim:

1. A vending machine including a casing, a bowl arranged at the upper part of the casing, said bowl being adapted to receive articles to be dispensed, said bowl having a centrally positioned aperture, means for rotating said bowl, a double cone guard positioned near the bottom of the bowl and over said aperture, a spirally shaped wall formed with more than one convolution so as to present a spiral passageway, said wall being carried by the lower wall of said double cone guard 15 and positioned to receive articles from the bowl and guide them through said passageway to said aperture, said spirally shaped wall being spaced from the bottom of said bowl, and a discharge chute extending through said aperture and positioned to receive articles that have been guided to the aperture. 20

2. A vending machine including a support, an article carrying bowl carried by said support, spring actuated means for rotating said bowl, 30 said bowl being formed with an opening in the center of its bottom, manually actuated means for causing said spring actuated means to function, an article discharge chute extending through the opening in the bottom of said bowl 35 for directing an article to a discharge point, and an article discharge member having a spiral passageway for guiding articles to said discharge chute as said bowl rotates.

3. A vending machine comprising a casing, an article carrying bowl having an opening at the center in the bottom, said bowl being positioned adjacent the upper end of the casing, said bowl being adapted to receive the various articles to be vended, a rotary support for said bowl, spring 45 actuated means for causing said support and said bowl to rotate, manually actuated means for causing said spring actuated means to function, a double cone guard positioned in said bowl near the bottom thereof and over said opening, means 50 carried by the bottom of said double cone guard forming a spiral guideway having its discharge end near said opening, and an article discharge chute extending through said opening to receive 55 articles from said spiral guideway.

4. A vending machine comprising a casing, a bowl arranged at the upper part of said casing, said bowl being adapted to receive articles to be dispensed, said bowl having a centrally positioned aperture in its bottom, a support for said bowl, means for rotating said support and said bowl, a stationary shaft extending through said aperture, stirring arms carried by said shaft, a double cone-shaped guard carried by said shaft and positioned near the bottom of the bowl and over the aperture therein, a depending wall carried by the bottom of said double cone-shaped guard forming a spiral passageway positioned to receive articles from said bowl and guide them to said aperture, and a discharge chute extending 65 through said aperture and positioned to receive articles from the outlet end of said passageway. 70

PHILIP C. HUGHES.
